UNITED STATES PATENT OFFICE.

HENRY KNIGHT, OF JERSEY CITY, NEW JERSEY.

IMPROVEMENT IN MACHINES FOR MOLDING CEMENT PIPE.

Specification forming part of Letters Patent No. 35,692, dated June 24, 1862.

To all whom it may concern:

Be it known that I, HENRY KNIGHT, of Jersey City, in the county of Hudson and State of New Jersey, have invented a new and useful Improvement in Machines for Molding Cement Pipes; and I do hereby declare that the following is a full, clear, and exact description of the same, reference being had to the accompanying drawings, forming part of this specification, in which—

Figure 1 is a vertical transverse section of a cement molding-machine with my improvements applied to it. The parts are in operative position, and a cement pipe is shown as molded by the machine. Fig. 2 is a section of the same in a longitudinal direction, the parts being out of operative position. A cement pipe is within the mold, and the mold lowered upon a truck, ready to be moved to the position indicated in red lines, in which position it is ready to be lifted out of the machine. Fig. 3 is a horizontal section of the machine in the line $\alpha\alpha$ of Fig. 1. Figs. 4 and 5 are details of the machine.

Similar letters of reference in the several figures indicate corresponding parts.

The nature of my invention consists, first, in the combination of centrally-perforated table, intermediate centrally-perforated and movable platform, adjustable mold or flask, adjustable base supporting and centering plate, adjustable core, and a jack-screw or its equivalent, all in such manner that a cement pipe with a square socket in one end is produced without the necessity of lifting the mold and pipe above the core; second, in the combination of the foregoing with a railway and a truck, so that when the pipe has been molded it, while in the mold, may be lowered upon the truck, clear of the top centering-table, and run out from under the same to a position for being lifted off of the machine; third, in the combination of a pliable washer with the hard shoulder or enlarged base of the core, for the purpose of relieving the cement about the square socket of the pipe while the core is being withdrawn; fourth, in the construction of the lower or base centering and supporting plate of the mold in such manner that a portion of it opens and closes across its center on hinges, for the purpose of admitting the largest end of the

mold and then clamping it in position; fifth, in the manner of arranging the guides of the rack of the jack-screw and the grooves of the frame of the machine so that they control the core, and yet do not interfere with its up movement; sixth, in connecting the shoulder or base of the core to the core by means of a pin or other adjustable connection, so that the shoulder may be withdrawn or applied, as necessity may require; seventh, it consists in a manner of lifting the base-plate and the flask or mold above the truck-platform.

To enable others skilled in the art to make and use my invention, I will proceed to describe its construction and operation.

A is the frame of the machine. It consists of four upright posts placed on a square base-block and united by cross-ties and a top piece or table, B, which table has a circular aperture through its center.

C is a hollow column extending up from the center of the base-block and uniting with a strong cross-tree, D, of the frame.

E are two short posts mounted upon the cross-tree and extending up and uniting with cross-ties of two railway-bars, F F, which are firmly bolted to the inner sides of the main posts of the frame A. The posts E E are grooved from top to bottom on their inner sides, so as to admit steadyng and guiding tongues of the jack-screw.

G is a T-shaped rack-bar, arranged so as to rise and descend in the hollow column and fitted and steadied, so as to move truly, by means of tongues or guides a a thereof, between the grooved posts E E.

H is a pinion, and H' a friction roller. The former is arranged in front and the latter behind the rack-bar. One gives motion to the rack-bar by gearing with it and the other eases its up and down movements. The pinion is on a crank-shaft, H², which is boxed on top of the cross-tree.

I is a core of cylindric form mounted upon the upper end of the rack-bar. The base of this core is enlarged in diameter by means of a cylindric collar, J, placed around it and fastened by a through-pin, b, which can be readily withdrawn as its ends protrude. The upper surface of this collar is made pliable by being faced with a soft-leather, rubber, or metal

washer, *c*, said washer encircling the smaller diameter of the core.

L is a wheeled platform or truck with a circular aperture through its center. This platform is mounted by means of its wheels upon the railway-bars *F F*.

K is a base plate or board for the flask or mold. It is mounted upon the truck *L*, and through its center an aperture of about the same diameter as the collar *J* of the core *I* is cut. To the upper side of this base board or plate two flaps, *d d*, are hinged, said flaps having under-beveling semicircular recesses *e e* formed in their meeting edges. These recesses when united form a circle equal in circumference to the outer circumference of the flask or mold at its base or largest diameter.

M is a mold or flask of ordinary construction, being divided vertically into two parts and made with two different diameters, *s t*, so as, in connection with the collared core, to mold pipe with extending collars and inner square sockets or shoulders. This mold rests vertically upon the base board or plate, and is centered concentric with the aperture therein by means of the flaps *d d* and confined in that condition by the same. A further centering is effected by means of the circular aperture in the top or table *B*, when the parts are adjusted for receiving the cement into the mold in the following manner: The mold being placed and confined upon the base plate or board, the truck is run in under the table until the circumference of the smaller portion of the mold is concentric with the aperture in the table. The jack-screw *G H* is now caused to elevate the core until its collar *J* enters the mold or flask the distance of the desired depth of the socket to be formed in the cement pipe. At this stage the protruding ends of the through-pin *b* comes in contact with the under side of the base board or plate at opposite points, and by reason of the further operation of the jack-screw they elevate the base-plate and mold off of the truck and cause the upper end of the mold to enter the central aperture of the table *B* till its edge comes even with the top surface of said table, as illustrated in black in Fig. 1. In this condition of the parts the cement is introduced from the table *B* into the mold and compactly forced down around the core. When the mold has been filled and a "striker" applied to the upper part of the molded cement pipe, a narrow ring-collar is forced down into the cement, as shown at *f*, so as to form a narrow shoulder at the small end of the pipe. The pipe is now finished, and after being allowed to "set" sufficiently the jack-screw is operated so as to withdraw the core gently. As the core descends the pliable washer peels off from the cement at the place where the square shoulder is formed, and thus saves the

shoulder from strain and injury. With the descent of the core the mold and pipe and base board or plate also descend and rest upon the platform-truck. The core having cleared the mold and the mold having cleared the table *B*, the truck is run out on the railway-bars, the flaps raised, and the cement pipe within the mold is removed from the machine. Another mold is brought into use and adjusted to the machine in the same manner as previously described.

With my invention pipe with square sockets at one end and also extending collars are molded, and by modifying the form of the mold and the core pipe with square sockets simply at one end and square shoulders at the other end may be produced; or, if desirable, pipe without sockets but with extending collars may be made by taking off the base-collar of the core; or pipe with collars which project very slightly may be produced by reducing the larger diameter of the core and the larger diameter of the mold and using the ring-collar *f* to form a shoulder on the outer upper end of the cement pipe. I, however, prefer pipe with collar and socket, such as represented.

What I claim as my invention, and desire to secure by Letters Patent, is—

1. The combination of the table *B*, movable platform *L*, mold or flask *M*, plate *K*, core *I*, and jack-screw *G H*, or its equivalent, the whole constructed and arranged and operating substantially as and for the purposes described.
2. The combination of the wheeled truck *L* and railway-bars *F F*, with a cement-pipe-molding machine, substantially in the manner and for the purpose described.
3. The combination of the pliable washer with the hard shoulder of the core, substantially as described, and for the purpose set forth.
4. The construction of the plate *K* with flaps *d d* and with apertures of different diameters, substantially as and for the purpose described.
5. The manner of arranging the guides *a* and the short posts *E E* with the rack-bar *G* and core *I*, for the purpose set forth.
6. The connection of the shoulder or collar *J* to the core *I* by means of an adjustable through-pin, *b*, in the manner and for the purpose described.
7. The lifting of the base-plate *K* and the flask or mold above the truck-platform by means of the ends of the pin *b*, or an equivalent means, substantially as described.

HENRY KNIGHT.
